UNITED STATES PATENT OFFICE.

HENRI C. BABIZE, OF FULLERTON, CALIFORNIA.

WOODWORKING MACHINE.

Application filed June 1, 1926. Serial No. 112,996.

My invention relates to wood working machines, and a purpose of my invention is the provision of an extremely simple, durable and comparatively inexpensive wood working machine which is capable of being readily converted into a rotary disk saw machine, a reciprocating scroll saw machine, and a wood turning lathe from either of the two machines, or vice versa, and in any state of conversion operating to effectively perform the functions for which that particular machine is intended. The machine in its adaptation as a wood turning lathe may also function as a grinding wheel, buffer, polishing wheel and drill.

I will describe only one form of wood working machine embodying my invention and will then point out the novel features thereof in claims.

In the accompanying drawings,

Figure 1 is a view showing in front elevation one form of wood working machine embodying my invention in its adaptation as a rotary disk saw machine;

Figure 2 is a view showing the machine in plan with the table thereof removed and portions of the machine in section;

Figure 3 is a view showing in rear elevation a wood working machine in its adaptation as a reciprocating scroll saw machine;

Figure 4 is a fragmentary view showing the carriage of the machine in its uppermost position;

Figure 5 is a view taken at right angles to Figure 1 and showing the machine in its adaptation as a wood turning lathe;

Figure 6 is a detail perspective view of the table embodied in the machine.

Similar reference characters refer to similar parts in each of the several views.

Referring specifically to the drawings, my invention, in its present embodiment, comprises a lower frame F of rectangular form connected to an upper frame F' of substantially corresponding form through the medium of uprights R arranged at the corners of the frames, all as clearly shown in Figure 2. The upper frame F' includes a strap 15 of linear form to which is bolted a strap 16 of substantially U form in order to provide at one side of the machine a recess in which a carriage K is adapted to work. As shown in Figure 1, an L-shaped frame F² is bolted to the lower frame F at its lower end and to the upper frame F' at its upper end, it being

noted that the upper end is bent to extend above and across one arm of the U-shaped frame 16, as clearly shown in Figure 2. Secured to the frame F² adjacent its upper end is a U-shaped bracket 17 in which is mounted an axle 18 that constitutes a pivot for mounting the carriage K in the bracket 17, one end of the axle being extended to provide a mounting for a plurality of grooved pulleys P.

The carriage K comprises an elongated flat arm, the outer or free end of which is bored to rotatably receive therein a tubular shaft 19 confined against longitudinal movement in the carriage by a collar 20 and a spacing ring 21 (Figure 2). The collar end of the shaft is provided with a nut 22 which confines pulleys P' on the shaft between the collar and the nut and trained about one of these pulleys is an endless belt 23 which provides an operative connection between the shaft 19 and one of the pulleys P. The opposite end of the shaft 19 is exteriorly threaded to receive a head 24 which co-operates with a ring 25 to securely clamp a rotary disk saw 26 thereto. It is to be noted that the corresponding end of the shaft 19 is open for the reception of various forms of head centers 27, one form being shown in Figure 2 and another form in Figure 5.

A motor M is bolted to the frame F² and its shaft 28 is provided with a grooved pulley 29 operatively connected to one of the pulleys P by a belt 30, whereby the motor is energized and the pulleys P will be driven and such motion transmitted to the shaft 19 through the belt 23 and the pulleys P'. In view of the provision of a plurality of pulleys P and P' it will be clear that the shaft 19 can be driven at different speeds. To eliminate slack in the belt 30, a tension pulley 31 (Figure 1) is provided and which is mounted on an arm 32 adjustably secured to one corner rail R.

The carriage K is capable of occupying three positions, an upper extreme position, as shown in Figures 4 and 5, an intermediate position as shown in Figure 1, and a lower extreme position as shown in Figure 3. In the upper extreme position, the carriage functions as a head stock of a lathe, and in this position the carriage is held against movement by the provision of a slot 33 in a table T, the latter comprising a flat body as shown in Figure 6, which is secured to the upper

frame F' by bolts 34 and 35. The bolt 34 extends through a bracket 36 secured to the frame F as shown in Figure 2, while the bolt 35 extends through the upper end of the frame F².

In applying the table T to the frame F', the carriage K is first swung to the upper extreme position and then the table is applied so that the slot 33 receives the carriage and 10 when the table is bolted in position the walls of the slot 33 function to hold the carriage against lateral movement in either direction. As shown in Figure 6, the table T is provided with a T-shaped groove 37 in longitudinal 15 alignment with the slot 33 and reinforced by the provision of metal strips 38. Within the groove 37 is adapted to slide bolts 39 and 40 for a tail stock 41 and tool rest 42, respectively, with the tail stock provided with a 20 tail center 43 which is adapted to co-operate with the head center 27 in supporting a piece of work between the stocks so that the work can be rotated upon rotation of the shaft 19. From this description, it will be manifest 25 that in this adaptation of the machine, it functions as a wood turning lathe, the saw 26 having been removed from the shaft 19 and a suitable head center 27 inserted in the open end of the shaft. It is to be noted that 30 the open end of the shaft is tapered so as to receive the tapered point of the head center and to thereby lock the center to the shaft so as to be rotated therewith.

In the intermediate position of the carriage K as shown in Figures 1 and 2, it is rigidly supported by a turn buckle B, the lower end of which is pivoted in a bracket 44 secured to the frame F². The upper end of the turn buckle is pointed to normally 35 repose within a recess 45 formed in the under side of the carriage K at a point adjacent the free end of the carriage so that the turn buckle functions as a rigid support for maintaining the carriage in the intermediate position. In this position of the carriage, the 40 saw 26 is secured to the shaft 19, while the table T is turned ninety degrees from the position described in its use as a support for the head and tail stocks so that a slot 46 is 45 positioned to receive a portion of the saw 26, as shown in Figure 1. In this new position of the table T the same bolts 34 and 35 are 50 employed to secure the table to the frame F' but they extend through other openings in 55 the table, as will be clear from a consideration of Figure 6. In this second adaptation of my invention, the machine functions as a 60 rotary disk saw machine with the saw 26 projecting above the surface of the table T so that when the saw is rotated it can be employed for the sawing of wood as it is moved across the table.

In the lower extreme position of the carriage K as shown in Figure 3, the machine 65 may be converted into a reciprocating scroll

saw machine by the provision of a wheel 47 which is secured to the shaft 19, and a pitman rod 48 is centrally connected to the wheel at one end and pivotally connected to an ear 49 at the other. The ear 49 is secured to a saw 70 frame including parallel bars 50 and 51 connected by a cross bar 52 and rods 53 and 54, the cross bar being pivoted on a bolt 55 mounted in a bracket 56 secured to one edge of the table T by a bolt 57. A saw blade 58 75 is connected to the bars 50 and 51 and with the latter disposed at opposite sides of the table T the saw blade extends through a suitable opening 59 in the table. In the applied position of the scroll saw the table T 80 occupies the same position as described in connection with Figure 5, and with the shaft 19 rotating it will be manifest that the scroll saw frame is continuously rocked about the bolt 55 as a center to effect a reciprocation 85 of the saw blade 58.

In any one of the three uses of my invention, the motor M when energized operates to drive the several pulleys and belts to effect the ultimate rotation of the shaft 19 and 90 to thereby drive the head center, or the scroll saw, and by virtue of the driving connection between the motor and shaft 19 it will be manifest that the shaft can be driven, irrespective of the position which the carriage 95 occupies. In each instance, the shaft 19 is positively driven to effect the proper operation of the respective tool.

Although I have herein shown and described only one form of wood working machine embodying my invention, it is to be understood that various changes and modifications may be made therein without departing from the spirit of the invention and the spirit and scope of the appended claims. 100

I claim as my invention:

1. A wood working machine comprising a frame, a table adjustably secured to the frame and having a saw receiving slot and a carriage receiving slot, said table being capable of occupying two positions on the frame, a carriage mounted beneath the table to occupy two positions beneath the table and a third position above the table, a shaft journaled in and supported by the carriage, tool attaching means on the shaft by which a rotary disk saw is adapted to be attached to the shaft so that when the carriage is in one of the positions beneath the table the saw will be rotatably supported in extended position through 110 the saw receiving slot of the table when the table is in one of its positions, or a pitman attached to the shaft and operatively connected to a scroll saw mounted for rocking movement on the table and all when the carriage 115 is in the other position beneath the table, said table being in the other adjusted position and having an opening therein through which the blade of said scroll saw is movable, or a head center attached to the shaft so that when the 120

125

130

carriage is in a position above the table the head center will be rotatably supported above the table, said table occupying the second mentioned position and receiving and supporting the carriage against movement within the carriage receiving slot, and means by which the shaft can be rotated when the carriage is in any one of the three positions.

2. A woodworking machine comprising a frame, a table detachably secured to the frame and capable of occupying either of two positions on the frame, said table having a saw receiving slot and a carriage receiving slot, a carriage movably mounted on the frame to occupy a position beneath the table and another position above the table, a shaft journaled in and supported by the carriage and provided with tool attaching means by which a rotary disk saw can be secured on the shaft for extension through the saw receiving slot of the table when the latter is in one of its positions and the carriage occupies the position beneath the table, the table when removed from the frame permitting the carriage to be moved to its second mentioned position, said table when replaced upon the frame to occupy its other position receiving the carriage in said carriage receiving slot, the walls of which operate to support the carriage against movement, and means by which the shaft can be rotated when the carriage is in any of its positions.

3. A woodworking machine comprising a frame, a table detachably secured to the frame and capable of occupying one position on the frame and a second position on the frame, angularly disposed with respect to the first position, said table having a saw receiving slot and a carriage receiving slot, a carriage movably mounted on the frame to occupy a position beneath the table and another position above the table, a shaft journaled in and supported by the carriage and provided with tool attaching means by which a rotary disk saw can be secured on the shaft for extension through the saw receiving slot of the table when the latter is in one of its positions and the carriage occupies the position beneath the table, the table when removed from the frame permitting the carriage to be moved to its second mentioned position, said table when replaced upon the frame to occupy its other

position receiving the carriage in said carriage receiving slot, the walls of which operate to support the carriage against movement, and means by which the shaft can be rotated when the carriage is in any of its positions.

4. A woodworking machine comprising a frame, a table detachably secured to the frame and capable of occupying one position on the frame and a second position on the frame, right angularly disposed with respect to the first position, said table having a saw receiving slot and a carriage receiving slot, a carriage movably mounted on the frame to occupy a position beneath the table and another position above the table, a shaft journaled in and supported by the carriage and provided with tool attaching means to which a rotary disk saw can be secured on the shaft for extension through the saw receiving slot of the table when the latter is in one of its positions and the carriage occupies the position beneath the table, the table when removed from the frame permitting the carriage to be moved to its second mentioned position, said table when replaced upon the frame to occupy its other position receiving the carriage in said carriage receiving slot, the walls of which operate to support the carriage against movement, and means by which the shaft can be rotated when the carriage is in any of its positions.

5. A woodworking machine comprising a frame, a table adjustable on the frame to occupy either of two positions, the table having openings therein, a carriage movable on the frame to occupy a position beneath the table and another position above the table and having means by which a tool can be rotatably supported for extension through one of the openings in the table when the latter is in one of its positions and the carriage occupies the position beneath the table, the table when adjusted to occupy its other position on the frame, receiving the carriage in the other opening in the table when the carriage occupies its second mentioned position so as to support the carriage against movement, and means by which the tool supporting means of the carriage can be driven when the carriage occupies either of its positions.
